UNITED STATES PATENT OFFICE.

GEORGE BUMGARDNER, OF CHICAGO, ILLINOIS.

BALLOT-MARKING MECHANISM.

1,361,226.

Specification of Letters Patent. Patented Dec. 7, 1920.

Application filed April 24, 1919. Serial No. 292,339.

To all whom it may concern:

Be it known that I, GEORGE BUMGARDNER, a citizen of the United States, residing at Chicago, in the county of Cook and State 5 of Illinois, have invented a certain new and useful Improvement in Ballot-Marking Mechanisms, of which the following is a specification.

My invention relates to an improved 10 mechanism for marking ballots by which proper marking of the ballots is facilitated and by which tampering with the marked ballots after they are marked by the voter is prevented. My invention consists essentially 15 of a mechanism for stamping or embossing on the ballot opposite the desired candidates' names, an indicating character, as for example the letter "X", the face of which preferably is conformed to print the 20 character on the ballot and at the same time emboss the character in the paper of the ballot to prevent alteration subsequently. The embossing is preferably accomplished by using a yielding platen or matrix to support 25 the ballot, or a platen or matrix having a corrugated surface coöperating with similar corrugations in the face of the printing character. My invention also provides means for simultaneously marking a ballot 30 in the manner described, to vote for candidates for various offices, and means for inking the printing characters with indelible ink which by the marking operation is carried into the fiber of the ballot sheet to prevent 35 alteration. My marking mechanism also prevents voting for more than one candidate for the same office, where but one candidate is to be elected.

My invention will best be understood by 40 reference to the accompanying drawings, showing a preferred embodiment thereof, in which—

Figure 1 shows the mechanism in plan view in selecting position,

Fig. 2 shows the mechanism in front elevation in selecting position,

Fig. 3 shows the mechanism in front elevation in open position,

Fig. 4 shows the mechanism in front elevation in marking position,

Fig. 5 shows one of the operating hooks in front elevation, this view being taken along the line 5—5 in Fig. 1.

Fig. 6 is a side elevation of the hook 55 shown in Fig. 5,

Fig. 7 shows two of the printing blocks

in side elevation, this view being taken along the line 7—7 in Fig. 1,

Fig. 8 is a bottom view of one of the printing blocks, and

Fig. 9 is a detail view showing the relation between a marking character and a resilient platen.

Similar numerals refer to similar parts throughout the several views.

As shown in Figs. 1 to 4 inclusive, the mechanism for simultaneously marking the ballot for several offices consists of a base 15, provided with upwardly projecting brackets 16, which pivotally support at 17, 70 one edge of a rectangular frame 18. The base 15 is provided with a raised central portion 19, having a plane upper surface which preferably is provided with small corrugations 20 extending transversely 75 across said surface to support the ballot 21 to be marked.

The pivots 17 are contained in slots 22 in the brackets 16, springs 23 being supported by the base to engage the right hand side 80 of the frame to hold said pivots at the upper ends of said slots unless the frame is forcibly depressed.

The left hand side of said frame is similarly supported in raised horizontal position by springs 24.

A plurality of rods 25 extend laterally of the frame 18 between its side members to support the printing blocks 26 which may be moved laterally on said rods to different 90 desired positions. Each of the said blocks is provided in its front and back faces with grooves 27 to receive said rods. Said blocks are of such a height that the characters 28 on their lower faces are slightly above the 95 ballot 21 for the position of the frame 18 shown in Fig. 2 which is the selecting position of the mechanism. In this position each of the blocks 26, which is in alinement, as shown in Fig. 1, with one of the offices to 100 be voted for, may be moved laterally until in line vertically, with the vertical column of the ballot for the candidate desired for the corresponding office.

A fibrous ink roller 29 rotatably supported 105 at its ends in brackets 30 carried by the base, and preferably filled with indelible ink, is located immediately to the right of the portion 19, with its upper surface slightly above the plane of the printing faces of the blocks 110 26 for the position of the frame 18 shown in Fig. 2 so that as each block is moved from

its extreme right hand or initial position, to select a desired candidate, its printing face engages said roller and is inked ready for the printing operation. The printing faces 5 of the blocks 26 are preferably corrugated as indicated in Fig. 8 to coöperate with the similar corrugations 20 carried by the base 15.

To the right and left hand of the frame 18, 10 the base 15 supports shafts 31 and 32 in suitable brackets, said shafts have rigidly secured thereto cranks 33 and 34 respectively, connected by a link 35. The shaft 32 also has rigidly secured thereto an operating 15 lever 36. Each of said shafts carries two hooks 37 for depressing the frame 18. Each of these hooks, as shown in Figs. 5 and 6, is rotatably mounted upon an eccentric 38, rigidly carried by its supporting shaft. 20 Each hook 37 is provided with a projecting pin 39 supporting one end of a spring 40, the other end of which is secured to a pin 41 projecting radially from the eccentric 38. The spring 40 tends to hold the hook 37 in 25 the position indicated in Figs. 5 and 6 relatively to the eccentric 38 with the pin 41 resting against a stop pin 42 projecting laterally from the hook 37.

As a result of the construction described, 30 when the lever 36 is moved around to the right from the position indicated in Figs. 1 and 2, assuming that the blocks 26 have been positioned to indicate the wish of the voter operating the machine, the shafts 31 and 32 are rotated in opposite directions to move the pins 41 away from the pins 42, and the action of the eccentrics 38 is to move the hooks 37 and frame 18 and parts carried thereby toward the base and thus force the 35 inked corrugations of the characters on the blocks 26 against the ballot 21 and force the engaged portions of the ballot between said corrugations and the corrugations 20, thus 40 breaking the fibers of the ballot somewhat and applying the indelible ink to said broken 45 fibers as a result of which an impression is made that cannot be erased.

The lever 36 is then moved in the reverse direction until the shafts and hooks assume 50 the position shown in Fig. 3, for which position the frame 18 is clear of the hooks and is raised to vertical position and the marked ballot is removed. For this position of the frame, the blocks 26 slide freely on the rods 55 25 to their lower ends, thus removing any indication of the manner in which the ballot 21 has been marked and placing the blocks 26 in their initial position from which they 60 cannot be moved by the next voter without inking their printing characters in the manner above described.

The next voter, having a blank ballot to 65 be voted, comes to the machine, places the ballot on the corrugations 20, which is facilitated by the guide marks 43 and 44 on the

ballot and base respectively, and moves the frame 18 to the horizontal position shown in Fig. 2. The voter then makes his selection of candidates as above described, and moves the lever 36 from the position shown in Fig. 70 3 to that shown in Fig. 2, which moves the hooks into engagement with the frame 18, and continued movement of the lever moves the frame and printing blocks to the position shown in Fig. 4, after which the marked ballot 75 may be removed as above described.

If desired, the corrugated surface 20 may be replaced by a thickness of resilient material, such as rubber, as shown at 45 in Fig. 9, in which case the marking operation 80 bosses the characters in the ballot.

While I have shown my invention in the particular embodiment above described, it will be understood that I do not limit myself to this exact construction in carrying 85 out my invention, as I may employ any equivalents known to the art at the time of the filing of this application without departing from the scope of the appended claims.

What I claim is:

1. In a ballot marking machine, the combination of a base for receiving a ballot, a movable support carried by the base and having open, selecting and printing positions, a series of movable printing characters carried by said support, there being a character for each office to be voted for and a different position for each character for each candidate for the corresponding office, and means for moving said support from selecting to printing position to print 95 said characters upon a ballot.

2. In a ballot marking machine, the combination of a base for receiving a ballot, a movable support carried by the base and having open, selecting and printing positions, a series of movable printing characters carried by said support, there being a character for each office to be voted for and a different position for each character for each candidate for the corresponding office, and means for moving said support from selecting to printing position to print 100 said characters upon a ballot, said base and characters being corrugated to produce corresponding corrugated impressions on a ballot.

3. In a ballot marking machine, the combination of a base for receiving a ballot, a movable support carried by the base and having open, selecting and printing positions, a series of movable printing characters carried by said support, there being a character for each office to be voted for and a different position for each character for each candidate for the corresponding office, 110 means for moving said support from selecting to printing position to print said characters upon a ballot, said base and characters being corrugated to produce corresponding corrugated impressions on a ballot.

4. In a ballot marking machine, the combination of a base for receiving a ballot, a movable support carried by the base and having open, selecting and printing positions, a series of movable printing characters carried by said support, there being a character for each office to be voted for and a different position for each character for each candidate for the corresponding office, and means for moving said support from selecting to printing position to print said characters upon a ballot, said base having alining indications for properly locating a ballot thereon. 70
5. In a ballot marking machine, the combination of a base for receiving a ballot, a frame pivotally mounted on the base, bars extending across the frame, printing characters mounted to slide freely on said bars, said characters being spaced to correspond with the several offices to be voted for on a ballot and movement of said characters 80 on said bars selecting desired candidates for said offices, said frame having an open position to insert and remove a ballot, a selecting position permitting movement of said characters without contact with a ballot 85 to select desired candidates and a printing position for pressing said characters against a ballot, and means for moving said frame from its selecting to its printing position, said base having alining indications thereon 90 for locating a ballot on said base. 95
6. In a ballot marking machine, the combination of a base for receiving a ballot, a frame pivotally mounted on the base, bars extending across the frame, printing characters mounted to slide freely on said bars, said characters being spaced to correspond with the several offices to be voted for on a ballot and movement of said characters on 100 said bars selecting desired candidates for said offices, said frame having an open position to insert and remove a ballot, a selecting position permitting movement of said characters without contact with a ballot to 105 select desired candidates and a printing position for pressing said characters against a ballot, and means for moving said frame from its selecting to its printing position, said characters and base being corrugated to correspondingly corrugate a ballot by the 110 printing operation. 115
7. In a ballot marking machine, the combination of a base for receiving a ballot, a frame pivotally mounted on the base, bars extending across the frame, printing characters mounted to slide freely on said bars, said characters being spaced to correspond with the several offices to be voted for on a ballot and movement of said characters on 120 said bars selecting desired candidates for said offices, said frame having an open position to insert and remove a ballot, a selecting position permitting movement of said characters without contact with a ballot to 125 select desired candidates and a printing position for pressing said characters against a ballot, means for moving said frame from its selecting to its printing position, and an inking roller for inking said characters when the latter are moved from their initial 130

to their selecting positions, said characters and base being corrugated to correspondingly corrugate a ballot by the printing operation.

5 11. In a ballot marking machine, the combination of a base for receiving a ballot, a frame pivotally mounted on the base, bars extending across the frame, printing characters mounted to slide freely on said bars,
10 said characters being spaced to correspond with the several offices to be voted for on a ballot and movement of said characters on said bars selecting desired candidates for said offices, said frame having an open position to insert and remove a ballot, a selecting position permitting movement of said characters without contact with a ballot to select desired candidates and a printing position for pressing said characters against
15 a ballot, and means for moving said frame from its selecting to its printing position, said means comprising rock shafts, devices connecting them for simultaneous operation, an operating handle secured to one of said shafts, and devices carried by said shafts engaging said frame for its selecting position to move said frame to its printing position upon operation of said handle.

12. In a ballot marking machine, the combination of a base for receiving a ballot, a frame pivotally mounted on the base, bars extending across the frame, printing characters mounted to slide freely on said bars, said characters being spaced to correspond with the several offices to be voted for on a ballot and movement of said characters on said bars selecting desired candidates for said offices, said frame having an open position to insert and remove a ballot, a selecting position permitting movement of said characters without contact with a ballot to select desired candidates and a printing position for pressing said characters against a ballot, and means for moving said frame from its selecting to its printing position, said means comprising rock shafts, devices connecting them for simultaneous operation, an operating handle secured to one of said shafts, devices carried by said shafts engaging said frame for its selecting position to move said frame to its printing position upon operation of said handle, and springs for supporting said frame in its selecting position.

55 13. In a ballot marking machine, the combination of a base for receiving a ballot, a frame pivotally mounted on the base, bars extending across the frame, printing characters mounted to slide freely on said bars,
60 said characters being spaced to correspond with the several offices to be voted for on a ballot and movement of said characters on said bars selecting desired candidates for said offices, said frame having an open position to insert and remove a ballot, a select-
65

ing position permitting movement of said characters without contact with a ballot to select desired candidates and a printing position for pressing said characters against a ballot, and means for moving said frame 70 from its selecting to its printing position, said means comprising rock shafts, devices connecting them for simultaneous operation, an operating handle secured to one of said shafts, eccentrics carried by said shafts, and 75 hooks mounted on said eccentrics for engaging said frame for its selecting position, motion of said handle in one direction operating said hooks to move said frame to its printing position and motion of said handle 80 in the reverse direction moving said hooks to clear said frame, thereby permitting motion of said frame to its open position.

14. In a ballot marking machine, the combination of a base for receiving a ballot, a frame pivotally mounted on the base, bars extending across the frame, printing characters mounted to slide freely on said bars, said characters being spaced to correspond with the several offices to be voted for on a ballot and movement of said characters on said bars selecting desired candidates for said offices, said frame having an open position to insert and remove a ballot, a selecting position permitting movement of said characters without contact with a ballot to select desired candidates and a printing position for pressing said characters against a ballot, and means for moving said frame from its selecting to its printing position, said means comprising rock shafts, devices connecting them for simultaneous operation, an operating handle secured to one of said shafts, eccentrics carried by said shafts, and hooks mounted on said eccentrics for engaging said frame for its selecting position, motion of said handle in one direction operating said hooks to move said frame to its printing position and motion of said handle in the reverse direction moving said hooks to clear said frame, thereby permitting motion of said frame to its open position, and springs for supporting said frame in its selecting position. 85 90 95 100 105 110

15. In a ballot marking machine, the combination of a base for receiving a ballot, a frame pivotally mounted on the base, bars extending across the frame, printing characters mounted to slide freely on said bars, said characters being spaced to correspond with the several offices to be voted for on a ballot and movement of said characters on said bars selecting desired candidates for said offices, said frame having an open position to insert and remove a ballot, a selecting position permitting movement of said characters without contact with a ballot to select desired candidates and a printing position for pressing said characters against a ballot, and means for moving said frame 115 120 125 130

- from its selecting to its printing position, said means comprising rock shafts, devices connecting them for simultaneous operation, an operating handle secured to one of said shafts, eccentrics carried by said shafts, and hooks mounted on said eccentrics for engaging said frame for its selecting position, motion of said handle in one direction operating said hooks to move said frame to its printing position and motion of said handle in the reverse direction moving said hooks to clear said frame, thereby permitting motion of said frame to its open position, and springs for supporting said frame in its selecting position, and an inking roller for inking said characters when the latter are moved from their initial to their selecting positions.
16. In a ballot marking machine, the combination of a base for receiving a ballot, a frame pivotally mounted on the base, bars extending across the frame, printing characters mounted to slide freely on said bars, said characters being spaced to correspond with the several offices to be voted for on a ballot and movement of said characters on said bars selecting desired candidates for said offices, said frame having an open position to insert and remove a ballot, a selecting position permitting movement of said characters without contact with a ballot to select desired candidates and a printing position for pressing said characters against a ballot, and means for moving said frame from its selecting to its printing position, said means comprising rock shafts, devices connecting them for simultaneous operation, an operating handle secured to one of said shafts, eccentrics carried by said shafts, and hooks mounted on said eccentrics for engaging said frame for its selecting position, motion of said handle in one direction operating said hooks to move said frame to its printing position and motion of said handle in the reverse direction moving said hooks to clear said frame, thereby permitting motion of said frame to its open position, and springs for supporting said frame in its selection position, and an inking roller for inking said characters when the latter are moved from their initial to their selecting positions, said characters and base being corrugated to correspondingly corrugate a ballot by the printing operation.
17. In witness whereof, I hereunto subscribe my name this 21st day of April, A. D. 1919.

GEORGE BUMGARDNER.
